UNITED STATES PATENT OFFICE.

GEORGE W. SCHODDE, OF NEW YORK, N. Y.

PIPE-SLEEVE.

1,210,217.

Specification of Letters Patent. Patented Dec. 26, 1916.

Application filed April 21, 1916. Serial No. 92,632.

To all whom it may concern:

Be it known that I, GEORGE W. SCHODDE, a citizen of the United States, and resident of New York city, borough of Queens, in the county of Queens and State of New York, have invented certain new and useful Improvements in Pipe-Sleeves, of which the following is a specification.

The object of my invention is to provide simple and efficient means to resist passage of gases, smoke and acid fumes, as well as the leakage of water from the surface of floors, around steam pipes, stand pipes, etc., passing through floors in buildings.

In carrying out my invention I embed or insert in the floors of buildings sleeves which encircle pipes passing through such floors, which sleeves rise above the surface of the floor to a suitable height, and I provide such sleeves with lateral extensions or flashings embedded in the floors to prevent leakage or seepage of water through the floors along the sleeves to the ceilings below the floors. Such sleeves are spaced from the pipe or fitted loosely thereon in such manner as to permit freedom for expansion and contraction of the pipe within the sleeves. Packing may be introduced between the sleeves and the pipes to prevent leakage between the sleeves and pipes in case of gases or smoke rising from below or water on the floor rising higher than the tops of the sleeves.

My invention further comprises novel details of improvement and combinations of parts that will be more fully hereinafter set forth and then pointed out in the claims.

Reference is to be had to the accompanying drawings forming part hereof, wherein,

Figure 1 is a vertical section illustrating my improvements installed in a floor; Fig. 1^a is a detail hereinafter referred to, Fig. 2 is a sectional view illustrating a modification, Fig. 3 is a vertical section illustrating a modification, and Fig. 4 is a section on the line 4, 4, in Fig. 3.

A pipe 1, such as for carrying water, steam, waste or the like, may be installed in a building in any usual or suitable manner, and as usual passes through the floors. At 2 is a sleeve or pipe section fitted in the floor and freely surrounding the adjacent portion of pipe 1. The upper edge of sleeve 2 is to be located at a suitable height above the surface of the floor to prevent water upon the floor, up to such height, from

flowing between the pipe and sleeve. The sleeve 2, at the lower portion within the floor, is provided with an extension 3 embedded in the floor. As illustrated in Fig. 1, such extension may be in the form of a wellknown flashing of suitable material. Such flashing may be of disk-like form having an aperture receiving the lower portion of sleeve 2, and said sleeve is shown provided with an annular exterior flange 4 to which the extension or flashing 3 may be secured in any suitable manner, such as by bolts or screws 5 passing through the flange, clamping a ring 6 against extension or flashing 3. At 7 is a supplemental or extension sleeve fitted within the floor entering sleeve 2 and spaced from pipe 1. The sleeve 2 may be of a substantial material, such as cast iron, brass or the like, while supplemental sleeve 7 may be of relatively thin inferior material, such as sheet iron, galvanized, tinned or the like. The supplemental sleeve 7 may have any desired number of extensions 8, such as angle pieces riveted or otherwise secured to the sleeve, embedded in the floor arch 9 when the latter is laid. The lower end of supplemental sleeve 7 may be flanged, or provided with one or more projections at 10, to temporarily rest upon the usual wooden bars or boards 11, that are installed to receive the floor arch 9 when the latter is laid. Tacks or the like, indicated at 12, (Figs. 1 and 1^a) may be driven through flange or projection 10 into the boards 11 to temporarily retain supplemental sleeve 7 in position. Said tacks 12 are shown having shoulders to rest against flange or projection 10, whereby the boards 11 may be readily removed from below the sleeve 7 by withdrawing the boards from the tacks.

In order to provide means for readily packing the space between pipe 1 and sleeve 2 at the upper portion of the latter, I have shown sleeve 2 provided with an interior rib or projection 13 upon which a ring 14, preferably a split ring, may be placed, which ring may fit loosely against the interior of sleeve 2 and firmly against the exterior of pipe 1 when forced into place. At 15 is a packing, such as mineral wool or the like, forced into the space between pipe 1 and sleeve 2 upon ring 14, to resist passage of gases, smoke, acid fumes or water between pipe 1 and sleeve 2 from one floor to another.

Instead of providing sleeve 2 with an extension in the form of a flashing, as illustrated in Fig. 1, said sleeve 2^b may have an extension 3^a cast integrally therewith of desired diameter, as indicated in Fig. 2, to resist the seepage or passage of water downwardly along the outer surface of such sleeve or supplemental sleeve 7^b to the ceiling below. Instead of the supplemental sleeve terminating at its lower end within the floor arch, such sleeve may extend through the floor arch and through the plaster below the same, and the lower end of said sleeve may be turned inwardly at 7^a toward pipe 1, as illustrated in Fig. 2, serving as a guide against pipe 1 when the parts are being installed. Any suitable finish may be applied to the extending end of sleeve 7^b, such as ceiling rosettes and the like.

My improvements may be installed in a floor as follows: If the pipe 1 is erected in a building prior to the installation of the floors, the sleeves 2 and 7 and ring 14 may be applied upon the lengths of pipe before the latter are coupled together. When the boards 11 are placed in position for receiving the floor arches, the sleeve 2 may be slid along the pipe above such boards, and the sleeve 7 then may be rested upon such boards and the projections 10 tacked thereto to retain the sleeve in proper position around the pipe 1, the sleeve 2 then being held up above such boards in any suitable manner. The floor arch may then be laid upon boards 11 and embed sleeve 7. When the concrete filling at 9^a is to be installed, the sleeve 2 is lowered over the upper part of corresponding sleeve 7 to rest upon the respective floor arch 9, the sleeve 7 retaining the sleeve 2 in position around pipe 1, and then the concrete filling 9^a is installed and embeds sleeve 2 and its extensions or flashings leaving a suitable portion of sleeve 2 projecting above such filling. Thereafter the packing 15 may be inserted between the pipe and sleeve 2. When the boards 11 are removed, sleeve 7 will remain in position, since the sleeve, the extensions 8 and tacks 12 are embedded in the floor arch, and then the ceiling plaster 16 and finish at 17 may be applied as usual to the floor arch.

Instead of sleeve 7 or 7^b being supplemental to sleeve 2 or 2^b the latter sleeve 55 may be made sufficiently long in a single piece to extend through the ceiling, as shown at 2^c in Fig. 3. In such case sleeve 2^c may have projections at 10^a to rest upon boards 11, the inturned lower end 2^a of sleeve 2^c serving as a guide against pipe 1 when the installation is being made. The sleeve 2^c has the extension 3^b embedded in the material of the floor. The lower end of sleeve 2^c below the ceiling may be suitably 65 shaped and adapted to receive the ceiling

rosette in manner described with respect to sleeve 7^b of Fig. 2.

The filling 9^a may be extended up at 9^b, as illustrated in Fig. 3, in the form of a curb above the floor level around the portion of sleeve 2^c that extends above the floor, to prevent leakage of water between the floor and the sleeve 2^c which might occur at a joint between said sleeve and floor, the curb 9^b being preferably carried to the top 75 edge of sleeve 2^c before the water rises to the top edge of the curb and sleeve.

While I have illustrated the curb 9^b in Fig. 3, it will be understood that the same may be applied in connection with the arrangements illustrated in Figs. 1 and 2.

My improvements are simple and inexpensive to manufacture and install, and have the advantage of enabling the flooring to be securely fitted to the sleeve when being installed, so as to resist seepage or leakage of water from the floor to the ceiling below, as well as to resist the passage of gases, acid fumes and smoke around the pipe from floor to floor. Furthermore, since the portion of sleeve 2 projecting above the floor level extends for a suitable height, the water that accumulates on the floor by reason of overflow from surface pipes, washing the floors, or from fires, is prevented from leaking along the pipes to the ceiling below, yet pipe 1 has freedom for contraction and expansion through the floor and within the sleeve without the tendency of causing looseness between the pipe and floor, which would permit seepage or flow of water, gases etc. 100 through the floor along the pipe.

Having now described my invention what I claim is:—

1. The combination of a molded floor, a pipe fitted freely therein, and a sleeve embedded in the floor and extending above the same and freely surrounding the pipe, permitting expansion and contraction of the pipe within the sleeve, said sleeve having an extension extending laterally around the sleeve, said sleeve and extension embedded in the floor to prevent leakage of water through the floor along the exterior of the sleeve.

2. The combination of a molded floor, a pipe fitted freely therein, a sleeve embedded in the floor and freely surrounding the pipe, permitting expansion and contraction of the pipe within the sleeve, and a supplemental sleeve embedded in the floor and loosely receiving said pipe, said sleeves being fitted one to the other, one of said sleeves having a laterally disposed extension surrounding the sleeve embedded in the floor to prevent leakage of water through the floor along the exterior of the sleeve.

3. The combination of a floor, a pipe fitted freely therein, a sleeve fitted in the floor and extending above the same, and freely surrounding the pipe, permitting expansion and

contraction of the pipe within the sleeve, said sleeve having a flange, and a flashing secured to said flange, the flange and said flashing being embedded in the floor.

- 5 4. The combination of a molded floor, a pipe fitted freely therein, and a sleeve embedded in the floor and extending above the same and freely surrounding the pipe, permitting expansion and contraction of the
- 10 pipe within the sleeve, and having an in-turned end portion surrounding the pipe, said sleeve having an outward extension surrounding the sleeve and embedded in the floor between the upper and lower surfaces
- 15 thereof to prevent leakage along the sleeve within the floor.

5. The combination of a molded floor, a pipe fitted freely therein, and a sleeve em-

bedded in the floor and extending above the same and freely surrounding the pipe, permitting expansion and contraction of the pipe within the sleeve, said sleeve having an outwardly disposed extension embedded in the floor, the floor having a raised curb-like portion surrounding the upper portion 25 of the sleeve above the floor level to prevent leakage of water from the floor level between the sleeve and the floor.

Signed at New York city, in the county of New York and State of New York, this 30 20th day of April, A. D. 1916.

GEORGE W. SCHODDE.
